CLAIM

The ornamental design for a chair, as shown and described.

DESCRIPTION

FIG. 1 is a front, left perspective view of a chair, showing our new design;

FIG. 2 is a front, right perspective view thereof;

FIG. 3 is a left perspective view thereof;

FIG. 4 is a right perspective view thereof;

FIG. 5 is a front perspective view thereof;

FIG. 6 is a rear perspective view thereof;

FIG. 7 is a top view thereof; and,

FIG. 8 is a bottom view thereof.

The broken lines in the drawings illustrate portions of the chair that form no part of the claimed design.

1 Claim, 8 Drawing Sheets(56)
